COIL INNER TUBE SPACER

Robert Joseph La Valley, Detroit, Mich., assignor to
American Radiator & Standard Sanitary Corporation,
New York, N. Y.

Application January 24, 1957, Serial No. 636,035

5 Claims. (Cl. 257—254)

The present invention relates to a tube assembly wherein one tube is carried in spaced relation within another tube, and to a tube spacer element for use in this assembly.

It is common practice in heat exchangers or heating coils to position one tube in spaced relation within another tube. The latter may or may not be a finned tube, as desired. A heating medium such as steam may be introduced into one end of the inner tube for passage therethrough and the steam and condensate may then be returned through the outer tube. In some instances it is desirable to provide a series of orifices throughout the length of the inner tube through which steam and condensate can flow into the outer tube. In such an arrangement the condensate can be taken from either end of the tube assembly.

Certain problems arise in the construction and use of a tube assembly of the foregoing type. Since it is necessary that unimpeded flow be permitted between the coaxially disposed tubes, means must be provided for supporting the inner tube while allowing such flow to occur. This can be accomplished by supporting the inner tube at its opposite ends, but such an arrangement is undesirable from both the operation and cost standpoint.

From the standpoint of operation it is not satisfactory when long tube assemblies are required. It is found that the inner tube will have a different expansion than the outer tube causing the inner tube to sag which in turn may result in uneven heat distribution and may cause the orifices on the bottom of the inner tube to be closed by contact or near contact with the outer tube. Thus, in order to avoid these undesirable conditions it is found necessary to support the inner tube intermediate its ends.

Various means have been utilized to support the inner tube at spaced intervals along its length, but such means have proved to be relatively high in material cost as well as in the labor cost required to assemble the heating coils.

It is the principal object of the present invention to provide an improved tube assembly wherein inner and outer tubes can be assembled in coaxial and radially spaced apart relation by use of a relatively simple, low cost spacer element which will operate to maintain the tubes in uniformly spaced relation throughout all conditions of operation.

It is another object of the present invention to provide a spacer element for use in spacing coaxially disposed inner and outer tubings, said spacer element being formed from a loop of resilient wire or similar material adapted to fit between said tubes.

It is still another object of the present invention to provide a spacer element of the foregoing character wherein the wire loop is formed so as to have three circumferentially equally spaced points of contact on the inner tube and three similarly spaced points of contact on the outer tube, the two sets of contact points being out of phase by approximately sixty degrees (60°) to provide a balanced support between said tubes.

2

Other objects of this invention will appear in the following description and appended claims, reference being had to the accompanying drawings forming a part of this specification wherein like reference characters designate corresponding parts in the several views.

In the drawings:

Figure 1 is an elevation of one embodiment of the spacer element shown in a vertical plane;

Fig. 2 is an enlarged section of a tube assembly with the spacer element of Fig. 1 mounted in an operative position; and

Fig. 3 is a section taken on the line 3—3 of Fig. 2.

Before explaining the present invention in detail, it is to be understood that the invention is not limited in its application to the details of construction and arrangement of parts illustrated in the accompanying drawings, since the invention is capable of other embodiments and of being practiced or carried out in various ways. Also, it is to be understood that the phraseology or terminology employed herein is for the purpose of description and not of limitation.

Referring now to the drawings, a more detailed description of the invention will be given. The spacer element 10 may be made from wire, and a suitable material is spring tempered brass wire. The spacer element 10 is formed in any suitable manner into the shape shown in Fig. 1, which illustrates the shape of the spacer element 10 when in the plane of the drawing and before it is assembled in place in the tube assembly 12. The latter, for the purpose of this description, consists of the spacer element 10, the inner tube 14 and the outer tube 16.

The outer tube 16 is imperforate, and if desired, may have coil fins (not shown) on its outer surface. The inner tube 14 may have apertures or orifices 18 uniformly spaced along its bottom surface through which fluid, such as steam or condensate, may pass from the inner tube 14 into the outer tube 16, and may have a second series of apertures 20 extending longitudinally along the upper surface of the inner tube 14 at substantially uniformly spaced intervals for mounting the plurality of spacer elements 10. It is to be understood that apertures 18 and 20 need not be in separate series and in practice it is contemplated arranging the apertures 120 degrees apart and at longitudinal intervals. A limited few of such apertures will then be used for mounting spacer elements 10 and the remainder of the apertures will perform the function of apertures 18.

As seen in Fig. 1, the spacer element 10 is formed from a single piece of wire bent at the middle to form an external contact point 22 at the bottom of a V-shaped portion. The upper extremities of the V-shaped portion are turned inward toward one another to form external contact points 24 and 26. The terminal ends are then bent inward and together to form the tongue 28 which is adapted to fit into one of the apertures 20, as shown in Figs. 2 and 3, and forms an internal point of contact for the inner tube 14. Two other internal contact points are provided at 30 and 32 in the V-shaped portion for receiving the inner tube 14.

It will be observed that the three internal contact points 28, 30 and 32 are spaced circumferentially approximately 120 degrees apart so that they provide a three point support for the inner tube 14. The external contact points 22, 24 and 26 are also spaced circumferentially approximately 120 degrees apart, but are 60 degrees out of phase with the internal contact points 22, 24 and 26. Such external and internal contact points engage the outer and inner tubes respectively to maintain a uniform spaced relation therebetween.

As can be seen in Fig. 3, the spacer elements 10 are all inclined to the vertical. This occurs because a circle passing through the contact points 22, 24 and 26 is larger

than the internal diameter of outer tube 16. In assembly, after the spacer elements 10 have been passed over the inner tube 14 and the tongues 28 have been inserted in the apertures 20, the inner tube 14 may be inserted into the outer tube 16 causing the bottom contact points 22 to be pushed to one side. However, the resilient properties of the spacer elements 10 will cause firm contacts to be made at the six contact points described above, thereby maintaining the inner and outer tubes in uniformly spaced relation. Furthermore, it can be seen that different rates of expansion of the two tubes will not in any way affect the supporting of the inner tube 14 within the outer tube 16, because the spacer members 10 are free to slide on outer tube 16.

From the foregoing it will be understood that relatively low cost spacer elements 10 are provided which can be assembled in place in a simple manner. Also, if desired, the apertures 20 can be positioned in alignment with apertures 18 so that both apertures can be drilled in a single operation. The tube assembly can be put together with no adjustment of the spacer elements being required, and during operation the spacer elements can accommodate different axial movements of the tubes 14 and 16.

I claim:

1. In combination, an outer imperforate horizontally disposed tube, an inner tube of smaller diameter disposed coaxially within said outer tube, said inner tube having a first series of apertures longitudinally arranged through which fluid may flow from one to the other tube and a second series of apertures longitudinally arranged for mounting spacer elements, and a plurality of spacer elements disposed between said tubes for maintaining said tubes in spaced relation, said spacer elements being formed from resilient wire segments, each segment encircling the inner tube and having its ends extending into an aperture in said second series of apertures and being formed so as to contact said inner tube at two other points 120 degrees from said one aperture and from one another, each segment also being formed to contact said outer tube at three points 60 degrees out of phase with the three points of contact of said inner tube.

2. An article of manufacture for use in spacing two coaxially disposed tubes radially from one another comprising a one-piece resilient wire element bent to form a closed loop, said loop having three outwardly projecting contact points for engaging the inner wall of the radially outer tube, and three inner contact points for engaging the outer wall of the radially inner tube, said inner and outer contact points being out of phase with one another, the ends of said wire element being turned together into said loop for insertion into an aperture in the wall of

10

the inner tube for anchoring the wire element in place on the latter.

3. In combination an outer imperforate tube; an inner tube of smaller diameter disposed coaxially within said outer tube; a series of apertures longitudinally arranged in the wall of the smaller tube; and a plurality of spacer elements disposed between said tubes for maintaining said tubes in spaced relation; said spacer elements being formed from resilient wire segments, each segment encircling the inner tube and having its ends extending into one of the aforementioned apertures, and being formed to contact the inner tube at two other points; each segment also being formed to contact said outer tube at points out of phase with the three points of contact with said inner tube.

4. In combination an outer imperforate tube; an inner tube of smaller diameter disposed coaxially within said outer tube; a series of apertures longitudinally arranged in the wall of the smaller tube; and a plurality of spacer elements disposed between said tubes for maintaining said tubes in spaced relation; said spacer elements being formed from resilient wire segments, each segment encircling the inner tube and having its ends extending into one of the aforementioned apertures, and being formed to contact the inner tube at a point spaced from the apertures; each segment also being formed to contact said outer tube at points out of phase with the points of contact with the inner tube; each segment being located generally in a plane extending at an acute angle to the tube axes; whereby during installation of the tubes the segments may be mounted on the inner tube with their ends located in the apertures, after which the inner tube may be passed into the outer tube with a deflection of the segments but without any disengagement of the segment ends out of the apertures.

5. In combination an outer imperforate tube; an inner tube of smaller diameter disposed coaxially within said outer tube; a series of apertures longitudinally arranged in the wall of the smaller tube; and a plurality of spacer elements disposed between said tubes for maintaining said tubes in spaced relation; said spacer elements being formed from resilient wire segments, each segment encircling the inner tube and having its ends extending into one of the aforementioned apertures, and being formed to contact the inner tube at a point spaced from the apertures; each segment also being formed to contact said outer tube at points out of phase with the points of contact with the inner tube.
